UNITED STATES PATENT OFFICE

JOHN J. WILLIAMS, OF WHEELING, WEST VIRGINIA, ASSIGNOR TO HAZEL-ATLAS GLASS CO., OF WHEELING, WEST VIRGINIA, A CORPORATION OF WEST VIRGINIA

MACHINE FOR VACUUM SEALING

Application filed May 28, 1927. Serial No. 195,103.

The invention relates to machines for vacuum sealing jars, tumblers or other containers; and it possesses numerous novel features of construction and operation, which are highly desirable, and which will be apparent to those skilled in the art to which it relates, from the following detailed description, when taken in connection with the accompanying drawings; in which

10 Figure 1 is a perspective view of the complete apparatus.

Figure 2 is an elevational view of the lower portion of the machine, and showing various operating parts in section.

15 Figure 3 is a vertical sectional view of the upper portion of the apparatus; the sealing plungers being in their lowermost position.

Figure 4 is a detail view of one of the sealing plungers; the plunger being shown in a slightly elevated position.

20 Figure 5 is another detail view of one of the sealing plungers; the plunger being shown in a slightly more elevated position than in Figure 4.

25 Figure 6 is a detail horizontal sectional view taken on line 6—6 of Figure 4.

Figure 7 is a vertical sectional view of the upper portion of the machine; the section being taken at right angles to that shown in Figure 3.

30 Figure 8 is a horizontal sectional view of the sealing chamber, taken on line 8—8 of Figure 3.

Figure 9 is a horizontal sectional view 25 with parts omitted, taken on line 9—9 of Figure 3, and showing parts of the lubricating system.

40 Figure 10 is a detail plan view of one of the vertical guide rods of the pressing mechanism, and further illustrating part of the lubricating system.

Figure 11 is a detail perspective view of one of the plates for positioning the containers to be sealed.

45 Figure 12 is a vertical sectional view of the vacuum regulator valve.

Figure 13 is a vertical sectional view taken on line 13—13 of Figure 2; and illustrating more particularly the clutch mechanism 50 for the operating shaft.

Figure 14 is a detail plan view further illustrating the clutch mechanism.

Figures 15 and 16 illustrate further details of the clutch mechanism.

Figure 17 is a vertical sectional view of 55 the sealing chamber provided with a slightly modified positioning and sealing apparatus, for use in the simultaneous sealing of a plurality of containers.

Figure 18 is a similar sectional view, but 60 taken at right angles to Figure 17; and

Figure 19 is a horizontal sectional view taken on line 19—19 of Figure 17.

Referring to the drawings more in detail, numeral 1 indicates the sealing chamber, 65 which is mounted on the hollow column or pedestal 2. It may be mentioned at the outset that this hollow column or pedestal not only provides a housing for the mechanism for operating the sealing plungers, but also 70 constitutes a vacuum tank, whereby a source of vacuum is always instantly available for vacuumizing the sealing chamber and receptacle therein, as will be described hereinafter.

75 The sealing head, against which the containers are pressed is indicated by numeral 3, and this sealing head is provided with the usual rubber sealing pad 4. The sealing head is, of course, vertically adjustable for adaptation to the sealing of ware of different height; and for this purpose the head is carried by a rod 5 which is threaded through the roof of the sealing chamber and provided at its upper end with an operating handwheel 6; the lock 80 nut 7 being provided for maintaining the sealing head in adjusted position. The sealing head is also provided with a small passage 8 to maintain equal air pressure at both ends of the receptacle being sealed.

90 For the purpose of closing the sealing chamber, I provide the usual door 9, having a gasket 10, which presses against the face of sealing chamber walls, to hermetically seal the sealing chamber, when the door is in 95 lowered position. The door 9 is carried by a pair of arms 11, 11, which are pivotally mounted on a pair of brackets 12, 12, fixed to the wall of the vacuum chamber. For the purpose of maintaining the door in a sub- 100

stantially vertical position I provide a link 13, which is pivotally connected to the door and to one of the brackets 12; the link having a slot 14, preferably at its rear pivotal connection, to provide the door with a limited freedom of movement. A tie rod 15 connects the arms 11, 11, intermediate their ends, and a link 16 extends downwardly from this tie rod and is connected at its lower end to a slide rod 17 which is mounted for reciprocating movement in a bearing or bracket 18. The slide rod 17 is lifted by a cam, to be hereinafter described, and the door is thus lifted by reason of the link connection between the slide rod and the arms 11 which carry the door. It will be understood, of course, that the door falls by gravity into closed position when the position of the cam is such as to free the lower end of the slide rod.

20 The rear wall of the vacuum chamber is provided with a passage 19 communicating with a passage 20 of the vacuum release or air valve casing 21. This valve casing is provided with apertures 22, which communicate 25 with the atmosphere when the valve 23 is raised, but which are normally closed by said valve. A spring 24 forces the valve 23 downwardly into seated position; and for the purpose of lifting the valve to open the ports 22 30 and thereby break the vacuum in the sealing chamber, I have attached to the valve stem a link 25, which is lifted at the desired instant, by the same cam that controls the opening of the door 9, which cam will be described hereinafter.

35 It is desirable, of course, to control the degree of vacuum in the vacuum tank, and for this purpose I have provided a vacuum regulator valve 26, which is shown in detail in 40 Figure 12. The valve 26 is normally maintained closed by a coil spring 27, the tension of which may be adjusted by the knurled nut 28. A pin and slot connection between the 45 valve stem and its bearing prevents the stem from turning when the nut 28 is adjusted. When the desired degree of vacuum is exceeded, the valve will open momentarily against the pressure of the spring 27, and air will be admitted to the vacuum tank through the 50 ports 29.

55 The two sealing plungers are indicated by numeral 30, and the upper ends of these plungers are enlarged to form disc members 31, upon which rests the sealing plate 32. The plate 32 is not attached to the disc members, but merely rests thereon of its own weight, and is held against horizontal movement by pins 33 which are carried by the plate 60 and which fit into centrally arranged sockets provided in the disc members, as clearly shown in Figure 3. The preferred shape of the sealing plate 32 is shown in Figure 8, and it will be noted that the forward corners of 65 the plate are notched to receive the ledges 34

which project inwardly from the forward portion of the sealing chamber side walls.

For the purpose of properly positioning the containers on the sealing plate, I have provided guides 35, which are shown in detail in Figures 8 and 11. The ware to be sealed is of various shapes and sizes, and it is therefore necessary that these guides be adjustable. Such adjustment may be accomplished in various ways, but the specific structure that I preferably employ consists of a series of holes 36 at the rear of the sealing plate, and a pin 37 passes through a hole 38 in the guide and through any one of the series of holes 36. In Figure 8 I have shown the pins passing through the innermost hole of the series. The opposite end of each of the guide plates is provided with a slot 39 which receives a pin 40 passing through one of another series of holes 41. This slot 39 provides for a slight adjustment, without moving the pins into other holes; and for further adjustment the rear ends of the guides may be pivotally mounted at any one of the series of holes 36, and the pins for the forward ends may be mounted in any one of the series of holes 41.

90 The sealing plungers 30 pass downwardly through guide sleeves 42 which are bolted or otherwise attached to the base of the sealing chamber, as shown in Figure 3. Each of the sleeves 42 is provided with a plurality of vertical passages 43 which permit, at the desired times, communication between the sealing chamber and the vacuum tank. Each sleeve 42 has an internal flange 44 adjacent its upper end, which functions as a seat for a collar 45 provided on each of the plungers 30. It will be apparent that when the collar or valve 45 is seated, as shown in Figure 3, there can be no communication whatever between the sealing chamber and the vacuum tank. At the beginning of the upward stroke of the plunger 30, as shown in Figure 4, the collar or valve 45 is lifted from its seat, but it still has a sliding contact with the inner wall of the sleeve 42. Under such conditions there is a slight communication between the sealing chamber and the vacuum tank, so that there is a slight leakage of air from the sealing chamber to the vacuum tank upon the commencement of the upward stroke of the plunger. It will be noted, however, that the vacuum does not have its full effect on the sealing chamber until the collar 45 has moved upwardly a sufficient distance to free it from the sleeve 42, as illustrated in Figure 5. In this manner the sudden application of the full effect of the vacuum is avoided. While in Figure 4 I have illustrated the collar 45 as being of considerably less diameter than the interior of the sleeve, this has been exaggerated merely for the purpose of illustrating the operation, and 100

it will be understood that the collar and sleeve have a sliding fit.

The plungers 30 are normally maintained in their lowered position by means of coil springs 46 which embrace the sleeves 42 and exert a downward pressure against collars 47 threaded on the plungers adjacent the lower ends thereof.

In the operation of an apparatus of this character it is apparent that there will be a considerable breakage of ware unless means be provided to relieve the sealing plungers of any excess pressure. For this purpose, the operating rods for the plungers are 15 silently mounted; and this operating mechanism, which may be installed in or removed from the vacuum tank as a complete unit, will now be described, reference being had particularly to Figures 2, 3 and 9. Numeral 19 indicates an opening provided in one sidewall of the vacuum tank; said opening being closed, with an airtight seal, by a plate 49. This plate 49 is provided with inwardly extending brackets 50, which have bearings 25 51 at the inner ends thereof. Slidably mounted in these bearings are guide rods 52, which rods are fixed, at their lower ends, to a plate 53, by means of a shoulder 54 and nut 55, as clearly shown in Figure 2. Rods 30 56 for operating the sealing plungers are carried by this plate 53, in aligned position with respect to their respective sealing plungers 30. The rods 56 are slidably mounted in sleeves 57, and are normally forced upwardly 35 to their full extent by means of coil springs 58 which embrace the sleeves and operating rods and which exert an upward pressure against collars 59 threaded on the upper ends of the rods; the upward movement of the 40 operating rods, with respect to the plate 53, being limited by nuts 60 threaded on the lower ends of the rods below the plate. Mounted in appropriate bearings beneath the plate 53 is a roller 61, which has engagement 45 with a cam, to be described hereinafter, and by which cam the plate 53 and parts carried thereby are elevated, and thereby forcing the sealing plungers upward and causing the ware to be pressed against the sealing head 50 with the desired pressure. As the rods 56 are not fixed to the plate 53 but are slidably mounted therein and forced upwardly by springs 58, it is apparent that the springs will be compressed before any undue pressure can 55 be applied to the article being sealed.

In view of the fact that the above described operating parts are located within the vacuum tank, it is necessary that the lubrication be taken care of from the outside. The oiling system shown herein is carried by the removable plate 49 which also carries, as described above, the unit for operating the sealing plungers or rods. Two oil cups 62, provided with pet cocks 63, are carried by pipes 64 fitted to the plate 49. Leading in

wardly from the pipes 64 are pipes 65 which have an upturned portion 66 adjacent their inner ends, and are each provided with a downturned nipple 67 at their ends, positioned directly over the upper ends of the 70 guide rods 52. Referring particularly to Figures 3, 7, 9 and 10, it will be noted that the upper ends of the guide rods 52 are dished as indicated by numeral 68, and that a short 75 passage 69 leads downwardly therefrom and communicates with a lateral passage 70 which opens through the side of the rod. Thus when it is desired to lubricate the bearings 51 for the guide rods 52, it is only necessary to open the pet cocks 63 whereupon atmospheric pressure will cause the oil in the cups 62 to be ejected through the nipples 67 downwardly upon the upper dished ends of the 80 guide rods 52, whereupon the oil will pass through the vertical passages 69 and lateral passages 70 to lubricate the bearings 51. The surplus oil will reach the plate 53 which is dished, as indicated by numeral 71 on Figures 2, 3 and 9. A vertical passage 72 leads 85 downwardly from the dished portion of the plate to carry the oil to the bearing for the roller 61. It is thus apparent that this vacuum lubricating system constitutes a very simple means for lubricating the moving parts of the sealer operating unit, without the necessity of opening the vacuum tank.

Having described the various units of the apparatus, I shall now proceed with a description of the driving unit, which operates the apparatus either continuously or intermittently, and which is preferably mounted on the frame of the machine, so that the whole device constitutes one complete unitary structure. In the description of the drive unit, reference is to be had particularly to 100 Figures 1, 2, 13, 14, 15 and 16.

Numeral 73 indicates a motor which is preferably mounted on the base plate 74 and which drives a pinion 75 meshing with a gear 76 fixed to a shaft 77 operating an air pump 110 78. This pump communicates with the interior of the vacuum tank 2 by means of a pipe 79. The air pump is driven continuously by the motor 73, and consequently a vacuum is continuously maintained in the tank 115 2. The shaft 77 also carries a sprocket or pulley 80, which by means of a sprocket chain or belt 81 drives a sprocket or pulley 82. This sprocket or pulley 82, through a speed reduction gearing indicated generally by numeral 83, and mounted on a bracket 83', drives a gear 84 loosely mounted on the main shaft 85 which operates various elements in 120 a manner to be hereinafter described.

In order to operatively connect the gear 125 84 with the shaft 85, I provide a clutch member 86 which is keyed or otherwise fixed to the shaft. The clutch member has an appropriate opening 87 in which is slidably mounted a bolt 88. Extending laterally from 130

the sliding bolt is a pin 89, carrying a roller 90; and when this pin is free a spring 91 drives the bolt forward so that its end engages in one of a plurality of holes or sockets 92 provided in the gear wheel 84. A trigger 93 is pivoted at 94 on a bracket 95, and is normally urged upwardly against the lower side of the clutch member 86 by a vertically sliding finger 96 arranged in a socket 97 above a coil spring 98. The trigger 93 is provided with an inclined cam face 99 on one side, and this merges into an abruptly curved shoulder 100 which constitutes a pocket to receive the pin 89.

It has been seen that the trigger 93 is normally pressed upwardly against the underside of the clutch member 86. That is the position of the trigger when the mechanism is at rest; but when it is desired to commence a sealing operation this trigger must be moved downwardly to release the pin 89 and roller 90. To thus operate the trigger, I preferably provide a pedal 101 to which is attached a link 102 extending upwardly and attached at its upper end to the trigger 93. To start the sealing operation it is only necessary to depress the pedal 101 so that the trigger will be lowered, against the pressure of the spring 98, until the trigger frees the pin 89 and roller 90, whereupon the spring 91 will force the bolt 88 forward into engagement with one of the sockets 92 provided in the gear wheel 84. The clutch is thus thrown in, and the shaft 85 begins its rotation. In the case of intermittent operation, the pedal 101 is at once released, and the spring 98 forces the trigger upwardly against the underside of the clutch member 86. The shaft 85 continues to rotate, and during a single rotation it causes all of the sealing operations to be performed; that is, the machine passes through a complete cycle of operations during a complete rotation of the shaft 85. As this shaft nears the end of a complete rotation the roller 90 will be engaged by the cam face 99 of the trigger 93, whereby the sliding bolt 88 will be moved backwardly against the pressure of spring 91, until by the time the roller 90 reaches the curved shoulder or pocket 100, the shaft 85 has completed its single rotation, the bolt has been entirely withdrawn, and the shaft comes to rest; the parts remaining in this position until the pedal 101 is again depressed. If the machine is to be operated continuously instead of intermittently, it is only necessary to maintain the trigger 93 out of the path of the roller 90, as illustrated in Figure 13. In order to maintain the trigger out of the path of roller 90 the pedal 101 must be retained in its depressed position, and I accomplish this by any preferred form of latch, such for instance, as indicated generally on Figure 1 by numeral 103. It will be understood that when the pedal

101 is depressed and the latch 103 projected across it, the machine will continue to operate until the latch is withdrawn, thereby permitting the pedal to rise, and permitting the trigger to move upwardly into the path 70 of the roller 90.

To overcome the inertia of the moving parts and thus assist in stopping the machine, I provide an adjustable friction brake 104.

As stated hereinbefore the shaft 85 carries the cams for operating the various units of the device; and these cams and the associated parts will now be described.

A cam 105 is mounted on the shaft 85 outside of the vacuum tank, and is adapted to operate, in sequence, the vacuum release or air valve 23 and the door 9; reference being had particularly to Figures 1, 2, 7 and 13. Mounted on a wall of the vacuum tank is a rocker arm 106, provided with a roller 107 which is adapted to be engaged by the cam 105. When the cam 105 moves the rocker arm 106 upwardly, the link 25 causes the vacuum release or air valve 23 to be unseated; whereby the vacuum in the sealing chamber is broken by the admission of air through the ports 22. In Figure 1 I have illustrated the rocker arm 106 engaged by the cam 105, so that the air valve is in open position. When the cam releases the arm 106, the air valve 23 is instantly seated by means of the spring 24; the position of the rocker arm, when released from the cam, being illustrated in Figure 13.

Mounted on a bracket extending from a wall of the vacuum tank is a second rocker arm 108, provided with a roller 109 which is adapted to be engaged by the cam 105 immediately after the cam has engaged the first-mentioned rocker arm 106. The rocker arm 108 also carries another roller 110 engaging the lower face of the slide rod 17. When the cam 105 moves the rocker arm 108 upwardly the slide rod 17 is lifted, and through the link connection 16 with the tie rod 15 carried by the door arms 11, the door 9 is moved to open position. Figure 1 clearly illustrates the position of the various parts when the rocker arm 108 has been moved upwardly by the cam. When the cam releases the rocker arm 108 the door falls by gravity into its sealing position; the parts when in this position being illustrated in Figure 13. A coil spring 111, having its lower end attached to the rocker arm and its upper end attached to an adjustable rod 112, maintains the roller 110 of the rocker arm 108 in contact with the lower face of the slide rod 17.

The shaft 85 passes on through the walls of the vacuum tank; being suitably journaled therein, as clearly shown in Figure 2. Of course, the bearings for the shaft in the walls of the vacuum tank are air tight; and a suit-

able lubricating system (not shown) leads to both the inner and outer ends of the bearings. Mounted on the shaft 85, within the vacuum tank, is a cam 113, which engages 5 the roller 61 carried by the plate 53. The design of this cam is best illustrated in Figure 3, and it will be noted that it is provided with two lobes indicated by numerals 114 and 115. The first lobe functions to give the sealing 10 plate 32 its preliminary upward movement, to carry the receptacle to be sealed into close relation with the sealing head 3; and the second lobe, 115, forces the receptacle against the sealing head, thereby performing the 15 sealing operation. The receptacle to be sealed is indicated by numeral 116.

All of the foregoing description relates to a machine for sealing one receptacle at a time, but it will be understood that by slight 20 changes the machine may be employed for simultaneously sealing a plurality of receptacles; and in Figures 17, 18 and 19 I have illustrated the few minor changes that are desirable to convert the machine into a 25 double sealer. By reference to those figures it will be noted that the sealing plate 32 has been removed from the disc members 31 forming part of the sealing plungers 30; and the articles to be sealed are placed directly 30 on the disc members.

In the use of the device as a double sealer it is also necessary to employ a different 35 guide for positioning the articles to be sealed. For this purpose a threaded rod 117 is mounted in the rear wall of the sealing chamber, and secured to its inner end, as by a set 40 screw 118, is the double guide member 119, having two sets of converging guide plates 120, by means of which the two receptacles are positioned on the discs 31.

In the use of the device as a double sealer I also preferably employ a sealing head of 45 different shape than that employed in the single sealer. The sealing head is indicated by numeral 121, and is shaped to substantially 50 follow the contour of the wall of the sealing chamber. The sealing head is attached to the rod 5 by any suitable means, preferably by means of a screw 122, threaded into the end of the rod.

A complete cycle of operation of the machine will now be described, assuming that it is to be operated in intermittent fashion.

The motor 73 is continuously driving the 55 air pump 78 thereby maintaining a vacuum in the tank 2, ready for instant use. The motor 73 is also constantly rotating the gear 84, so that to start operations it is only necessary to depress the pedal 101. The attendant places in the sealing chamber the receptacle to be sealed, with the cap loosely mounted thereon; the receptacle being guided into proper position by the guides 35, or by the guides 120 if the machine is being operated as a double sealer. The operator now

depresses the pedal 101, whereby the trigger 93 releases the roller 90, and the bolt 88 is moved forwardly by the spring 91, into one of the sockets 92 in the gear wheel, thereby clutching the continuously rotating gear 70 wheel with the shaft 85. The shaft thus begins to rotate, and the operator releases the pedal 101, so that the trigger 93 will move upwardly to assume its position in the path of the roller 90, whereby the clutch will be thrown out at the end of a complete rotation of the shaft, in the manner hereinbefore described.

As the shaft begins its rotation the lobe of 75 cam 105 will ride from under the rocker arm 108, thereby permitting the door to close by gravity. The further rotation of the shaft 85 brings the lobe 114 of cam 113 into engagement with the roller 61 of the plate 53, thereby giving the sealing plungers 30 their preliminary upward movement to bring the receptacles to be sealed into close relation with the sealing heads, so that the caps will not be displaced when a vacuum is created in the sealing chamber. When the plungers 30 are 80 in their lowermost position the valves or collars 45 are seated on the flange 44, and hence there is no communication between the sealing chamber and the vacuum tank. But the instant the plungers commence their preliminary upward movement the valves are 85 unseated, thereby providing a slight communication, or what may be termed a leakage, between the sealing chamber and the vacuum tank. However, as soon as the collar 45 passes out of the sleeve 42, the vacuum has its 90 full effect on the sealing chamber.

Further rotation of the shaft 85 brings lobe 95 115 of cam 113 into engagement with roller 61, whereby the sealing plungers are given 100 their final upward movement, to press the receptacles against the sealing head, so that the cap will be forced thereon. The lobe 115 of cam 113 is so designed that the sealing plungers will be immediately moved to their 105 lowermost position, shutting off communication between the sealing chamber and the vacuum tank. At this point in the operation the cam 105 comes into engagement with the rocker arm 106, whereby the valve 23 is lifted 110 to break the vacuum in the sealing chamber.

Further rotation of the shaft 85 will bring 115 cam 105 into engagement with the rocker arm 108, whereby the door 9 will be opened, and the sealed article is ready to be removed. The complete cycle of operation has been 120 performed, and the clutch bolt 88 is withdrawn by the engagement of roller 90 with the inclined face 99 of the trigger 93, so that the shaft 85 comes to rest at the end of a complete revolution, with the roller 90 in the pocket 100 of the trigger 93. Another 125 receptacle is positioned in the sealing chamber.

ber, the pedal 101 is again depressed, and the operation is repeated.

If the machine is employed for simultaneously sealing a plurality of receptacles the 5 operation remains identically the same as described above, and to adapt the machine to the simultaneous sealing of a plurality of receptacles, it is only necessary to change a few 10 of the accessories, such as guides, sealing heads, etc.

The foregoing description relates to the intermittent operation of the machine. If the machine is to be operated continuously, either for sealing a single receptacle at a time, 15 or simultaneously sealing a plurality of receptacles, it is only necessary to retain the pedal 101 in its lowered position, as by the use of a latch 103, so that the trigger 93 is retained out of the path of roller 90. It is 20 obvious that under such conditions the shaft 85 will have a continuous rotation instead of an intermittent one, so that as soon as one cycle of operation is completed the next cycle 25 will begin.

From the foregoing description it will be 25 apparent to those skilled in the art, that the invention includes numerous novel and desirable features, which make the machine both economical and efficient in operation.

It will also be apparent that the machine 30 is subject to numerous changes and modifications, all of which I aim to include within the scope of the appended claims.

What I claim is:

1. In a vacuum sealing machine, a sealing 35 chamber, a sealing plunger, a pedestal supporting the sealing chamber, said pedestal constituting a vacuum tank, a shaft journaled in the walls of the vacuum tank, and a cam carried by said shaft and adapted to operate 40 said sealing plunger.

2. In a vacuum sealing machine, a sealing 45 chamber, a sealing plunger, a pedestal supporting the sealing chamber, said pedestal constituting a vacuum tank, a shaft journaled in the walls of the vacuum tank, and means 50 operated by said shaft for giving the sealing plunger a preliminary upward movement and a final upward movement.

3. In a vacuum sealing machine, a sealing 55 chamber, a vacuum tank associated therewith, a stationary sealing head, a reciprocable sealing plunger, and means carried by the sealing plunger for shutting off communication between the sealing chamber and 60 vacuum tank when the plunger is in its lowermost position.

4. In a vacuum sealing machine, a sealing 65 chamber, a vacuum tank associated therewith, a stationary sealing head, a reciprocable sealing plunger, and means controlled by the sealing plunger to open a slight communication between the sealing chamber and the vacuum tank as the sealing plunger begins its upward stroke.

5. In a vacuum sealing machine, a sealing chamber, a vacuum tank associated therewith, a sealing head, a reciprocable sealing plunger, and means controlled by the sealing plunger to vary the extent of communication between the sealing chamber and the vacuum tank during the upward movement of the sealing plunger. 70

6. In a vacuum sealing machine, a sealing chamber, a vacuum tank associated therewith, a sealing head, a reciprocable sealing plunger, and means controlled by the sealing plunger to open a slight communication between the sealing chamber and the vacuum tank as the sealing plunger begins its upward stroke and increasing the extent of communication upon further upward movement of said sealing plunger. 75

7. In a vacuum sealing machine, a sealing chamber, a vacuum tank associated therewith, a plunger movable in the sealing chamber, and means operated by said plunger for shutting off communication between the sealing chamber and vacuum tank when the plunger is in inoperative position and opening communication as the plunger leaves its inoperative position. 80

8. In a vacuum sealing machine, a sealing chamber, a stationary sealing head, a reciprocable sealing plunger, a pedestal supporting the sealing chamber, said pedestal constituting a vacuum tank, a sleeve surrounding 85 said sealing plunger, and a collar carried by the sealing plunger and movable into the sleeve to control communication between the sealing chamber and the vacuum tank. 90

9. In a vacuum sealing machine, a sealing chamber, a stationary sealing head, a reciprocable sealing plunger, a pedestal supporting the sealing chamber, said pedestal constituting a vacuum tank, a sleeve surrounding 95 said sealing plunger, an internal flange provided on said sleeve, and a collar carried by the sealing plunger and adapted to seat on said flange to shut off communication between the sealing chamber and the vacuum tank. 105

10. In a vacuum sealing machine, a sealing chamber, a sealing plunger, a vacuum tank associated with the sealing chamber, a reciprocable rod for operating said plunger, a member carrying said rod, a guide rod also carried by said member, said guide rod having a passage leading from the upper end of the rod to its bearing, and a vacuum oiling 110 system for feeding oil to the upper end of said rod.

11. In a vacuum sealing machine, a sealing chamber, a sealing plunger, a vacuum tank associated with the sealing chamber, a reciprocable rod for operating said plunger, a member carrying said rod, a guide rod also carried by said member, a roller carried by said member, a cam adapted to engage said roller for elevating said sealing plunger, and 115

- 5 a vacuum oiling system for feeding oil to
said guide rod and from said guide rod to
said roller.
- 10 12. In a vacuum sealing machine, a sealing
chamber, a door therefor, a vacuum release valve
associated with said sealing chamber, a rotatable
shaft, and a single cam carried by said shaft for
opening the door and the vacuum release valve.
- 15 13. In a vacuum stationary sealing machine,
a sealing chamber, a door therefor, a vacuum tank
directly associated with the sealing chamber, a valve
regulating the degree of vacuum in the vacuum tank, a
vacuum release valve for the sealing chamber,
20 a sealing plunger, a rotatable shaft, and cams
carried by said shaft for operating the door,
the vacuum release valve and the sealing
plunger.
- 25 14. In a vacuum stationary sealing machine,
a sealing chamber, a door therefor, a vacuum tank
directly associated with the sealing chamber, a valve
regulating the degree of vacuum in the vacuum tank, a
vacuum release valve for the sealing chamber,
30 a sealing plunger, a rotatable shaft, and means
controlled by said shaft within the vacuum tank
for operating the sealing plunger.
- 35 15. In a vacuum stationary sealing machine,
a sealing chamber, a door therefor, a vacuum tank
directly associated with the sealing chamber, a valve
regulating the degree of vacuum in the vacuum tank, a
vacuum release valve for the sealing chamber,
40 a sealing plunger, a rotatable shaft, means
within said vacuum tank controlled by the
shaft for operating the sealing plunger, and
means without said vacuum tank controlled
by the shaft for operating the door and the
vacuum release valve.
- 45 16. In a vacuum stationary sealing machine,
a sealing chamber, a door therefor, a vacuum tank
directly associated with the sealing chamber, a valve
regulating the degree of vacuum in the vacuum tank, a
vacuum release valve for the sealing chamber,
50 a sealing plunger, a rotatable shaft, cams
carried by said shaft for operating the door,
the vacuum release valve and the sealing
plunger, means for driving said shaft, a
clutch for connecting said driving means and
55 the shaft, and means for automatically
throwing out said clutch when the shaft has
made a complete revolution.
- 60 17. In a vacuum stationary sealing machine,
a sealing chamber, a door therefor, a vacuum tank
directly associated with the sealing chamber, a valve
regulating the degree of vacuum in the vacuum tank, a
vacuum release valve for the sealing chamber, a
sealing plunger, a rotatable shaft, cams carried
65 by said shaft for operating the door, the
vacuum release valve and the sealing plunger,
- er, and means whereby said shaft may be
rotated continuously or intermittently.
- 70 18. In a vacuum stationary sealing machine,
a sealing chamber, a door therefor, a vacuum tank
directly associated with the sealing chamber, a valve
regulating the degree of vacuum in the vacuum tank, a
vacuum release valve for the sealing chamber,
75 a sealing plunger, a rotatable shaft, cams
carried by said shaft for operating the door,
the vacuum release valve and the sealing
plunger, means for driving said shaft, a
clutch for connecting said driving means and
80 the shaft, means for disengaging said clutch
at the end of a complete revolution of said
shaft, and means for rendering said releasing
means inoperative, whereby the shaft
may rotate continuously.
